Patented Nov. 18, 1913.

UNITED STATES PATENT OFFICE.

GEORGE DUPES, OF KNOXVILLE, TENNESSEE.

RAILROAD JOINT-CROSSING.

1,078,724.

Specification of Letters Patent.

Patented Nov. 18, 1913.

Application filed April 22, 1913. Serial No. 762,962.

To all whom it may concern:

Be it known that I, GEORGE DUPES, a citizen of the United States, residing at Knoxville, in the county of Knox and State of Tennessee, have invented a new and useful Railroad Joint-Crossing, of which the following is a specification.

The device forming the subject matter of this application is adapted to be used in connection with a railroad weighing scale for the purpose of alining the rail section supported by the platform of the scale, with another rail section supported independently of the movable platform of the scale.

One object of the present invention is to provide a device of the type above mentioned, in which a vertically movable member cooperates with a pair of guides, thereby to effect an alining of the rails.

Another object of the invention is to provide a device of this type in which the vertically movable member is normally upheld, yieldingly, in position for engagement by the wheel of a passing car, to aline the rail sections.

Another object of the invention is to provide a device of this type by the means of which the wheel of the railway vehicle will be eased down upon the platform supported rail section, thereby preventing an undue vibration of the scale beam.

It is within the scope of the invention to improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawing: Figure 1 shows the invention in perspective; Fig. 2 is a longitudinal section; Fig. 3 is a transverse section; and Fig. 4 is a side elevation showing a modification.

In the drawings, the vertically moving weighing platform of the scale is denoted by the numeral 1.

The numeral 2 indicates a fixed support, such as the frame, ground or floor, which surrounds the edge of the platform 1. A

rail 3 is secured to the support 2 and is in approximate alinement with a rail 4 which is secured to the platform 1.

Mounted upon the support 2 in close relation to the rail 3 is a guide 5. Another guide, denoted by the numeral 6, is mounted upon the platform 1 and in close relation to the rail 4. The guides are substantial duplicates, and but one of them need be described in detail. Each guide comprises a base 7, having an upstanding rib 8. That face of the rib 8 which is adjacent the rail is inclined, as indicated at 9. Securing elements 12 pass through the bases 7 of the guides 5 and 6, and serve to hold the guides respectively, in place upon the support 2 and upon the platform 1. Each guide is provided, at one side of the rib 8 with recesses 14. Securing elements 15, engage the platform 1 and in the support 2 project downwardly through the guides at the bases of the recesses, and constitute means for supporting the respective guides 5 and 6 against movement. Other securing elements 11 extend into the recesses 14 and connect the side of the guides with the rails.

A vertically movable member is provided, the same in the present instance taking the form of a tongue 18 pivotally held in place by means of a bolt 16, loosely engaged in an opening 17 formed in the tongue adjacent one end thereof, the bolt 16 entering the guide 5. A resilient means is provided, for normally holding the free end of the tongue 18 uplifted, the resilient means, in the present instance, taking the form of a helical compression spring 20, fitting in one of the recesses 14, the upper end of the spring 20 exerting a pressure against the lower face 95 of the tongue 18. Upon its upper edge, and adjacent at its ends the vertically movable member or tongue 18 is beveled as indicated at 21.

Presupposing that the parts are positioned as shown in Figs. 1 and 2, the operation of the device is as follows: A railway vehicle wheel, rolling along the rail 3 will encounter the beveled portion 21 of the tongue 18 which is located adjacent the pivot element 16. The tongue 18 will thus be depressed, and as the tongue is depressed, it will ride along the inclined inner faces 9 of the ribs 8 of the guides 5 and 6. By this operation, a lateral movement will be imparted to the platform 1, and the rails 3 and 4 will be alined, so that the wheel of the railway ve-

hicle may pass readily from one rail to the other. It is to be observed that as the wheel rides up onto the crown of the tongue 18, the wheel is lifted off the meeting ends of 5 the rails, the tongue thus acting as a bridge when the wheel passes from one rail to the other. All danger of derailing the vehicle, as the same proceeds upon the platform 1 will thus be avoided. When the wheel rides 10 off the free end of the tongue 18, the bevel 21 which is adjacent the free end of the tongue will serve to ease the wheel onto the rail 4. The bevels 21, therefore, serve to prevent violent movement of the platform 15 1 and, consequently, prevent forcible oscillations of the scale beam. So soon as the vehicle wheel is free from the end of the tongue 18, the spring 20 will restore the tongue 18 to the position shown in Figs. 20 1 and 2.

The device herein disclosed, although simple in construction, and comprising few parts, is thoroughly efficient as a means for alining properly, a rail section upon a platform of a scale, and a fixed, independently supported rail section.

The device is adapted to be used on turn tables and under like conditions, in which the tongue must be inverted or turned back 30 in order that the turn table may rotate. Referring to Fig. 4 the guide 50 which is adjacent the fixed rail 51 is provided with an ear 52 through which passes a pivot element 53 engaging the tongue 54. This arrangement, replacing the bolt 16, gives the tongue a greater range of vertical movement.

From the foregoing it will be obvious that in use the device is by no means confined 40 to a scale platform.

Having thus described the invention, what is claimed is:—

1. In a device of the class described, a

pair of guides having side faces inclined with respect to the vertical; and a vertically 45 movable tongue coöperating with the side faces of the guides.

2. In a device of the class described, a pair of guides; a vertically movable tongue coöperating with the side faces of the 50 guides; and rail sections located at the sides of the guides, the rail sections being supported independently of the guides.

3. In a device of the class described, a pair of guides; and a vertically movable 55 tongue coöperating with the guides, one end of the tongue being beveled upon its upper edge.

4. In a device of the class described, a pair of guides; a tongue pivoted to one guide 60 and adapted to coöperate with the side faces of both guides; and a spring interposed between the tongue and one guide.

5. In a device of the class described, a pair of guides; a tongue pivoted to one guide 65 and beveled upon its upper edge, adjacent both ends; and resilient means for elevating the tongue.

6. In a device of the class described, coöperating parts comprising a guide and a tongue, one of which coöperating parts is provided with a beveled face, engageable by the other part when the tongue is moved, to produce relative horizontal movement between said coöperating parts in a direction 75 at right angles to the plane of movement of the tongue; and means for supporting the tongue pivotally, independently of the guide.

In testimony that I claim the foregoing 80 as my own, I have hereto affixed my signature in the presence of two witnesses.

GEORGE DUPES.

Witnesses:

SELINA WILSON,
I. E. SIMPSON.
